UNITED STATES PATENT OFFICE.

WILLIAM S. SMITH, OF LANGDON, NORTH DAKOTA.

DEVICE FOR TREATING SEEDS.

No. 806,999.

Specification of Letters Patent.

Patented Dec. 12, 1905.

Application filed June 12, 1905. Serial No. 264,912.

To all whom it may concern:

Be it known that I, WILLIAM S. SMITH, a citizen of the United States, residing at Langdon, in the county of Cavalier and State of North Dakota, have invented a new and useful Device for Treating Seed, of which the following is a specification.

This invention relates to devices for treating seeds of various kinds previous to planting for destroying deleterious germs and other harmful objects or growths.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages.

In the drawings, Figure 1 is a perspective view of the improved apparatus in operative position. Fig. 2 is a longitudinal sectional elevation with the seed-receptacle in discharging position in full lines and in draining position in dotted lines. Fig. 3 is a perspective view of the implement employed for skimming the floating particles of foreign matter from the liquid solution.

The improved device comprises a tank 10 for the compound or solution, of any required size and of any suitable material, but preferably of wood lined with zinc, galvanized iron, copper, or other material, as at 11, which will resist the action of the solution, and with handles 12 for carrying from place to place. Disposed within the receiving-tank 10 is a receptacle 13 for the seed to be treated, having inclined ends 14 15 and perforated bottom 16 and hinged, as at 17, at one end to one end of the receiving-tank. Swinging, as by a hinge 18, from the free end of the receptacle 13 is an arm or lever 19, which serves the two purposes of a means for elevating the receptacle into a draining or discharging position, as represented, respectively, in dotted lines and by full lines in Fig. 2, and also as a prop to support the receptacle in its partially-elevated

position when the contents are to be drained, as illustrated in dotted lines in Fig. 2. To this end the free end of the arm 19 is pointed to enter the earth, as represented at 20, to prevent slipping and also to permit the arm to be set at any desired point to control the degree of inclination of the receptacle. When not in use, the arm 19 lies lengthwise of the receptacle and tank, as in Fig 1.

Attached at opposite sides of the tank member 10 are spaced guides 22 23 and 24 25, with keepers 26 27, respectively, at the upper ends of the guides, and engaging these keepers and bearing between the guides are the ends of a U-shaped member 28 to form a stop to limit the movement of the receptacle 13 and hold the same in partly-overturned position, as shown in full lines in Fig. 2, while the contents are discharged. By this simple arrangement by placing the solution which is to be employed for treating the seed in the tank 10 and placing the seed in the receptacle 13, with the latter lowered into the tank, the seed will be thoroughly saturated with the solution and the deleterious germs or other harmful matter or growth destroyed, and when the action is completed the receptacle is elevated into the position shown by dotted lines in Fig. 2 by drawing it upward with the pull rod or lever 19 and arranging the same as a prop until the seeds are thoroughly drained, when the receptacle is partly overturned for resting on the stop member 28, and thus discharging the treated seeds over the end of the tank, the inclined ends of the receptacle facilitating the discharging action and preventing the saturated seeds from lodging in the receptacle.

Any of the various seeds—such as wheat, corn, oats, rye, or the like, which are liable to be affected by "smut" or other deleterious germs or harmful objects or growths, or potato-seed, which are subject to "scab" or other similar growths—may be treated effectually and in any required quantities or for any required length of time. Any of the various solutions or compounds usually employed may be used, as will be obvious.

Some kinds of grain contain light foreign matter, which will float upon the solution within the receptacle 13, and for the purpose of removing such material a skimming implement 29 is provided, as in Fig. 3.

Having thus described the invention, what is claimed is—

1. In a device of the class described, a re-

- ceiving-tank for the solution, a receptacle for the product and adapted for seating in said receiver and provided with a perforated bottom, said receptacle hinged to said receiver for 5 swinging from the same, and an arm hinged to the free end of said receptacle and swinging therefrom, and serving as a pull-rod to elevate the receptacle and as a prop to support the same in partly-overturned position.
- 10 2. In a device of the class described, a receiving-tank for the solution, a receptacle for the product and adapted for seating in said receiver and provided with a perforated bottom, said receptacle hinged to said receiver

for swinging from the same, spaced guides 15 upon the sides of said receiving-tank, keeper members at the upper end of said guides, a U-shaped bar for passing by its ends beneath said keepers and between said guides, and forming a stop to limit the movement of said 20 receptacle when partly overturned.

In testimony that I claim the foregoing as my own I have hereto affixed my signature in the presence of two witnesses.

WILLIAM S. SMITH.
